(57) **CLAIM**

The ornamental design for a round floodlight fixture, as shown and described.

DESCRIPTION

FIG. 1 is a bottom perspective view of the floodlight fixture shown mounted to a pole;

FIG. 2 is a top perspective view of the floodlight fixture shown mounted to the pole, a central top region of the fixture being shown in phantom lines;

FIG. 3 is a front elevation of the floodlight fixture with the pole not shown;

FIG. 4 is a rear elevation of the floodlight fixture with the pole not shown;

FIG. 5 is a left side elevation of the floodlight fixture with the pole not shown, the right side elevation being a mirror image;

FIG. 6 is a top plan view of the floodlight fixture shown mounted to the pole, a central top region of the fixture being shown in phantom lines; and,

FIG. 7 is a bottom plan view of the floodlight fixture shown mounted to the pole.

The phantom lines are provided for illustrative purposes only and form no part of the claimed design.
